CLAIM

The ornamental design for a trampoline pole cap, as shown and described.

DESCRIPTION

FIG. 1 is a bottom perspective view.

FIG. 2 is a side perspective view.

FIG. 3 is a bottom right perspective view.

FIG. 4 is a front view.

FIG. 5 is a back side view.

FIG. 6 is a left side view.

FIG. 7 is a right view.

FIG. 8 is a top view; and,

FIG. 9 is a bottom view.
